UNITED STATES PATENT OFFICE.

GEORGE ILLIAS, OF DALLASTOWN, PENNSYLVANIA.

IMPROVEMENT IN WATER-ELEVATORS.

Specification forming part of Letters Patent No. 44,315, dated September 20, 1864.

To all whom it may concern:

Be it known that I, GEORGE ILLIAS, of Dallastown, in the county of York and State of Pennsylvania, have invented a new and useful Improvement in Water-Elevators; and I do hereby declare that the following is a full, clear, and exact description thereof, which will enable others skilled in the art to make and use the same, reference being had to the accompanying drawings, forming part of this specification, in which—

Figure 1 shows a plan of the apparatus, the top H of the frame being removed so as to see the shaft and the parts below it. Fig. 2 is an elevation of a cross-section on the red line in Fig. 1.

Similar letters of reference indicate like parts.

A represents the elevator, which is to be made of convenient dimensions to suit the well or cistern. The floor E of the platform is to be raised, as shown, upon the sills, and holes for the passage of the buckets are cut through them, as shown at g. Metal strips n are fastened to the floor for the rollers e of the movable platform B to run upon. The platform B is made of a width ample to cover the bucket-holes g, and guides f project from its under side at either end, passing down through slots s, cut in the floor E, as seen in both figures.

A wire post, h, is attached to the outer front edge of the movable platform, by which to move it to and fro. Other slots, i, are also cut in the movable platform to receive the chain a when the platform is rolled over the holes g.

The top frame, H, rests upon the standards A', and the wire b, is secured to it, as shown, directly over the wheel D. This wire extends down on each side of the chain, and terminates on each side in a fork, the office of which is to arrest the bucket by embracing its bottom part, as shown in red outline in Fig. 2. The shaft F passes through the standards A' and runs upon friction-rollers,

(as seen in Fig. 1,) which are mounted in metallic boxes S. A groove, x, is cut around the shaft at one end for one pair of friction-rollers to run in, to prevent end-play of the shaft. A ratchet-wheel, J, is secured upon the shaft, and detents j, which engage it, one on each side, are supported upon a bracket, Q, beneath. A trough, C, with a spout, V, is secured at one end to one of the standards A', and the other end is supported by metal straps or rods O, which are secured to the top frame, as shown in Fig. 2.

D is a sprocket-wheel, grooved, which carries the chain to which the buckets c are attached. The trough is cut away, as seen at U', to receive and support the sides of the bucket when it is tilted, and a hook is secured to the sides of the trough at the center of each opening, to catch upon the top edge of the bucket as it ascends and so cause it to be tilted over the trough. The shaft F is turned by a crank, or by any other convenient device. The movable platform is suitably protected and strengthened by metal straps 1.

The operation of the apparatus is plainly to be seen from the foregoing description.

Having thus described my invention, I claim as new and desire to secure by Letters Patent—

1. The movable platform B, constructed substantially as shown, in combination with the flooring of the main platform E, substantially as described.

2. The combination of the double buckets, the chain, and sprocket-wheel, the forked rod, b, the trough C ratchet with double detents, and the driving-shaft, substantially as described.

3. The combination of the movable platform with the devices enumerated in the claim next preceding, substantially as described.

GEORGE ILLIAS.
